LEVI BRANSON, OF RALEIGH, NORTH CAROLINA.

Letters Patent No. 85,990, dated January 19, 1869.

GEOGRAPHIC GAME.

The Schedule referred to in these Letters Patent and making part of the same.

To all whom it may concern:

Be it known that I, LEVI BRANSON, of Raleigh, in the county of Wake, and State of North Carolina, have invented a new and improved Geographical Game; and I do hereby declare that the following is a full, clear, and exact description of the construction and operation of the same, reference being had to the accompanying drawings, making a part of this specification, in which the board or table employed in the game, and forming a part of my invention, is represented by a plan.

The object of this invention is to produce an interesting and agreeable game, the successful playing of which shall depend entirely upon the skill of the player, and which cannot be played by any one without his acquiring thereby a vast amount of correct information as to the conformation, extent, population, and resources of the geographical divisions and subdivisions of the earth, or of some particular continent, nation, or territory thereof.

The instruments necessary for the game are—

First, a table, somewhat resembling a carom-table for billiards, with or without spring-cushions around it, and having on its surface a correct delineation of any part of the earth's surface that it may be considered most important to study, according to the age, progress, condition, or dwelling-place of those who are expected to use the table; and,

Secondly, in connection with such table, a set of balls, (one, two, or more,) to be played on the surface of the table, with or without a cue, as may be preferred.

The table can be made with maps on both sides, and so that it can be used with one side or the other uppermost, and when so constructed, one side could have a large map, representing, for instance, the whole earth, while the other had a map of the country, state, or county where the table was to be used. These maps could all be attachable and detachable, so as to be changed at pleasure.

Instead of a large table, like that above described, a smaller and portable one, similar in size and shape to a chess-board or backgammon-board, might be employed, and in connection therewith, balls of smaller size, the dimensions and form of the apparatus being varied according to circumstances.

In connection with such table and balls, I mark, either upon the table within the limits of the division, or upon an independent counter-board, the name of each geographical subdivision shown by such map, and the figures denoting its population, area, wealth, and such other statistics or data as it may be desirable to teach in this way. There may be a slight depression at the site of the capital of a state, or of some important city, and the population of such city may also be marked.

In the drawing—
a a represent the cushions of the table, which en-

close, in this particular case, a map of several states of the American Union, with a portion of the contiguous sea.

To play this game, one party stations his ball at some particular point on the map to be agreed upon, (for instance in the open sea, at *x*,) and plays his ball so as to hit one of the opposite cushions, or so as to cross any line on the table, any river, chain of mountains, &c., and then to lodge in some state, as, for instance, in the State of North Carolina. He, or his second, then marks down on the counter-board, the name, population, area, wealth, or figures representing other statistics of that state, and if the ball lodges in the depression at the site of Raleigh, or of New York city, Charleston, or any other city, he marks down the population, or similar statistics of such city or town. All these sums added together give his score for that play or inning.

His opponent then proceeds to score in the same way, and at the expiration of ten, or any other number of plays or innings, as may be agreed upon, the sum of all the scores on each side is obtained by addition, and the player having the largest number is the winner.

Instead of scoring at the end of his own play, a more exciting game could be played if each player were to score at the end of his opponent's play, as follows, viz:

First player plays his ball, say, into New York city. He does not then score, but awaits his opponent's play. Second player then plays to strike first player's ball, drive it out of New York, and leave it in the Atlantic ocean, or in Lake Michigan, where it counts nothing, while his own ball goes to Philadelphia or New Orleans, where it counts heavily.

At the end of second player's play, first player scores according to the present situation of his ball, and then plays to drive his opponent into the water, and leave his own ball in a fortunate position, and so on to the end.

If it were too easy a shot to play directly on the ball lodged in New York city, the player essaying to remove it therefrom could be required to play his ball across some river, or against an opposite cushion, or to a certain distance, before his ball would be allowed to move the New York ball, and if he did not do so, should lose his shot.

Many other variations of the game might be suggested.

My design is not to indicate any particular rules by which the balls are to be made to traverse the table and get to their scores, but to describe the apparatus employed, and, in general terms, the way in which it can be used, so as to combine recreation and pleasure with instruction, to a degree difficult to attain in any other way.

Having thus described my invention,
What I claim as new, and desire to secure by Letters Patent, is—

1. The table for the geographical game above described, substantially as shown and specified.
2. The entire apparatus above described, consisting essentially of the table with map-surface, and the playing-balls, when combined together to produce a game, substantially in the manner set forth.

To the above specification of my invention, I have signed my hand, this 31st day of July, 1868.

LEVI BRANSON.
